CARTON CLOSING MECHANISM

George I. Hohl, East Orange, N. J.

Application October 28, 1943, Serial No. 507,977

8 Claims.

(Cl. 93—6)

This invention relates to automatic mechanism for closing filled cartons or boxes of the type provided with side tabs and end closure flaps having tuck-portions, and especially of the type wherein such form of end closure means is provided at each end of the carton or box, with the end closure flaps at both ends thereof extending from the same side and in a common plane.

The invention has for an object to provide a novel construction of automatic mechanism for first manipulating and closing the side tabs of the carton or box, and then simultaneously manipulating and closing the end closure flaps and tucking in the tuck-portions thereof at the respective ends of the carton or box.

The invention has for another object to provide novel automatic mechanism for the purposes stated whereby accurate folding of the end closure flaps and their tuck-portions under controlled guidance is so attained as to assure accurate presentation and direction of the tuck-portions for easy insertion into the interior of the carton or box body, whereupon to finally and simultaneously thrust home said tuck-portions with substantially no risk of distortion, tearing or other mutilation; all whereby rapid automatic closing of filled cartons as successively moved through the mechanism is obtained.

Other objects of this invention, not at this time more particularly enumerated, will be understood from the following detailed description of the same.

An illustrative embodiment of carton closing mechanism according to this invention is shown in the accompanying drawings, in which:

Fig. 1 is a side elevational view of the carton closing mechanism of this invention; Fig. 2 is a horizontal sectional view thereof, taken on line 2—2 in Fig. 1; Figs. 3, 4, and 5 are respectively transverse sectional views, taken respectively on lines 3—3, 4—4, and 5—5 in Fig. 1; Fig. 6 is a transverse sectional view taken on line 6—6 in Fig. 1, showing the relatively folded end closure flaps and tuck-portions as presented ready for closing of the former and tucking in of the latter; and Fig. 7 is a view similar to that of Fig. 6 but showing the completion of the closing of said end closure flaps and tucking in of their tuck-portions.

Fig. 8 is an enlarged fragmentary sectional view of end closure flap closing and tuck-portion tucking means ready to operate; and Fig. 9 is a similar view thereof after operation.

Similar characters of reference are employed 55

in the above described views, to indicate corresponding parts.

The carton closing mechanism is adapted to be incorporated in a machine for setting up and filling cartons whereby to close the filled cartons, and thereupon discharge them from the machine. Such carton setting up and filling machine, not being the subject of the instant invention, is not shown, and it will be understood that such setting up and filling machinery is, in principle, well known to the art, and may be variously designed to suit the particular product desired to be filled into the cartons, and, furthermore, may include, when the cartons are supplied thereto in initially flat or collapsed condition, suitable means for expanding the cartons to open condition, ready for the reception of the product to be filled thereinto.

The novel carton closing mechanism of this invention is especially adapted to manipulate that type of carton or box which comprises a rectangular hollow body 10 having open opposite ends, at each of which are provided inwardly foldable side tabs 11 and 12 and a foldable closure flap 13 having a relatively foldable tuck-portion 14 at its free end; said closure flaps 13 at both ends of the body 10 being disposed to extend from the same side of the body and initially in common plane therewith.

30 By way of illustration the carton closing mechanism of this invention is shown as operative upon cartons filled by a desired number of razor blades B which have been previously deposited therein by suitable blade supplying and filling mechanism; but it will be obvious that said carton closing mechanism is functionally indifferent to the particular kind of product which the carton encloses.

The carton closing mechanism according to 40 this invention comprises a conveyer means for receiving and supporting open cartons into which the content, e. g. razor blades B, has been inserted by suitable mechanism at a filling station from which the conveyer means leads or 45 extends, and by which the filled open cartons are carried to and through the carton end closure manipulating devices by which the novel carton closing mechanism of this invention is characterized. Said conveyer means comprises 50 a suitably supported and driven endless chain or similar carrier means 15 having affixed thereto, at spaced intervals, a succession of carton receiving pocket forming elements 16, the pockets formed thereby being transversely open end wise, so that filled cartons deposited therein

lie crosswise of the length of the conveyer. The upper or outgoing operative course of the conveyer means is disposed to run between laterally spaced platform members 17, which thus border opposite sides thereof, and, preferably, the outgoing course of said conveyer chain or similar carrier means 15 is supported against sagging by a track plate 18 disposed beneath and bridging the space between the platform members 17.

Mounted on the platform members 17 parallel to and so as to respectively border the respective laterally open ends of the conveyer pockets, as carried by the operative outgoing course of the conveyer chain or similar carrier means 15, and so as to lie contiguous to the ends of carton bodies 10 carried in said conveyer pockets, and also so as to overlie the closure flaps 13 of said carton bodies, are folder bars 19. Said folder bars 19 are supported from posts 20, which are affixed in upstanding relation to the platform members 17, by offset bracket arms 21 which extend between said posts and said folder bars, whereby the latter are so supported as to provide clearance for unimpeded movement beneath the same of the carton closure flaps 13 and their tuck-portions 14. The folder bars 19 are of such width and are so disposed that their outer substantially perpendicular faces are aligned with the lines of fold between the closure flaps 13 and their tuck-portions 14; said tuck-portions initially projecting freely beyond said outer faces of the folder bars. The rearward ends of said folder bars 19 are provided with chamfered nosings 22 divergent from their inner perpendicular faces, said nosings being operative to inturn the leading side tabs 11 of the carton bodies 10.

Mounted above and laterally offset from but parallel to the path of movement of the operative outgoing course of the carton conveyer means is a suitably driven power transmission shaft 23.

Means for inturning the trailing side tabs 12 of the carton bodies 10 is located adjacent to the rearward ends of the folder bars 19 and their nosings 22 so as to be cooperative therewith. This means comprises a transverse rock-shaft 24 suitably supported in a bearing bracket 25 above the operative outgoing course of the carton conveyer means. Affixed to said rock-shaft 24 is a pair of tab kicker members 26, disposed to depend therefrom so as to straddle the carton bodies 10 moved therebetween by the carton conveyer means. Also affixed to said rock-shaft 24, to extend upwardly therefrom adjacent to the power transmission shaft 23, is a crank-arm 27 provided at its end with a roller 28. Mounted on said power transmission shaft 23, so as to be rotated thereby, is a rock-shaft actuating cam 29, the cam face 30 of which operatively engages said crank-arm roller 28 so as to produce properly timed oscillation of said rock-shaft 24 and the tab kicker members 26 mounted thereon. Spring means 31 is provided to operatively maintain the crank-arm roller in engagement with said cam 29.

Mounted on the platform members 17, respectively in cooperative relation to the respective forward end portions of the folder bars 19, are suitably shaped turn-over bars. Said turn-over bars each comprise an upwardly inclined rear end portion 32 disposed to extend obliquely past the outer face of the forward end portion of an adjacent folder bar 19, such rear end portion being connected by an in-curved intermediate portion

33 so as to merge with a forwardly and horizontally extending forward end portion 34 which projects freely beyond the forward extremity of said folder bar 19, and so as to lie opposingly contiguous to upper parts of the open ends of carton bodies 10 carried along the same by the carton conveyer means. The inner sides of said intermediate and forward end portions 33 and 34 of the turn-over bars are shaped to provide a twisted or heliciform surface 35 leading from the substantially perpendicular inner face planes thereof toward but short of the planes of the undersides thereof. Said turn-over bars may be supported in the described attachment to the platform members 17 and described relations to the adjacent folder bars 19 by angle brackets 36 affixed to outer faces of the rear end portions 32 of the folder bars and to the top surfaces of said platform members.

Also mounted on the platform members 17, respectively in cooperative relation to the forward end portions 34 of the respective turn-over bars, are suitably shaped tilter plates 37 having downwardly inclined rearward end portions 38. Said tilter plates 37 are disposed beneath and contiguous to the forward end portions 34 of the adjacent turn-over bars with which they cooperate, and are fixedly supported in such relation by angle brackets 39 which are secured to and between the same and the platform members 17. The top surfaces of said tilter plates 37 are shaped to provide twisted or heliciform surfaces 40 leading from horizontal plane at the inclined rearward end portions 38 to an upwardly and outwardly inclined angular plane, usually approximating a forty-five degree angle; such angular plane surfaces being opposed to the downwardly and outwardly inclined angular plane portions of the heliciform surfaces 35 of the forward end portions 34 of said turn-over bars.

Located adjacent to the respective forward terminals of the associated turn-over bars and tilter plates, and thus on opposite sides of the carton conveyer means, are oscillatable push-plates 41, which at proper times function to cooperate with up-tilted carton end closure flaps 13 and their bent and inwardly directed tuck-portions 14, whereby to insert or tuck the latter into the open ends of the carton body 10 served thereby and move the former into closed relation to said carton body ends. The lower ends of said push-plates 41 are pivoted by hinging pintles 42 journaled in bearings 43 which are suitably supported from the platform members 17.

Aligned with the respective push-plates 41, are tuck-portion guide fingers 44 which project from tail-blocks 45, toward the carton bodies carried by the conveyer means. The free ends of said guide fingers 44 lie closely contiguous to the ends of a carton body 10 disposed therebetween, and are so positioned that their under surfaces 46 lie in substantially horizontal plane substantially coincident to but preferably slightly below the plane of the underside or inside surface of the top wall of said carton body as supported in a pocket of the carton conveyer means. The tail-blocks 45, from which said guide fingers 44 project, are adjustably mounted on fixed shafts 47, the latter being suitably supported from the platform members 17 by supporting brackets or posts 48. The tail-blocks 45 may be turned up or down about their supporting shafts 47, whereby to raise or lower the guide fingers 44 for adjustably disposing the same in the operative relation to said

carton body 10 above described, and when they are thus properly adjusted, may be fixed against displacement by tightening set-screws 48, with which said tail-blocks 45 are provided, in binding or gripping engagement with the supporting shafts 47. The upper free end portions of the push-plates 41 are indentingly cut away intermediate their sides as at 49 (see Figs. 2, 8 and 9 more particularly), so as to clear the stationary guide fingers 44 when said push-plates are turned by the means for actuating the same.

Mechanism is provided for producing properly timed operative oscillation of said push-plates 41 as each carton body 10 carried by the carton conveyer means is brought into and momentarily held in alignment therewith and therebetween. Such mechanism comprises a bridge plate 50 supported from the platform members 17 by columns 51, upstanding from the latter, so as to be spaced above and so as to straddle the carton conveyer means. Mounted upon said bridge plate 50 is a bearing block 52 disposed in vertical alignment relative to said carton conveyer means. Journaled in said bearing block 52, in parallel, spaced apart relation, are a pair of longitudinal rock-shafts 53. Affixed respectively upon the rearward ends of said respective rock-shafts 53 are dependent, normally outswung, lever arms 54. Each push-plate 41 is provided, at a side thereof and adjacent to its upper free end, with a roller stud 55 adapted to be engaged by a cooperating lever arm 54, when the latter is inswung. Carried by each lever arm 54 is an offset retractor yoke 56 adapted to embrace the roller stud 55 of the push-plate 41 with which the lever arm is cooperative, whereby to positively cause the push-plate to follow with corresponding movement the outswinging movement of said lever arm. Affixed respectively upon the forward ends of said respective rock-shafts 53 are spur gears 57, which are intermeshed together, whereby said rock-shafts 53 are caused to oscillate in respectively opposite directions so that inward and outward movements of said lever arms 54 are respectively simultaneously effected. Affixed upon one of the rock-shafts 53 is a crank-lever 58 which extends toward the hereinbefore mentioned power transmission shaft 23. Said crank-lever 58 is provided at its free end with a roller 59. Fixed upon said power transmission shaft 23, so as to be rotated thereby, is a cam 60, which is adapted to be engaged by the roller 59 of said crank-lever 58. Said cam 60 is suitably shaped to produce properly timed oscillatory movement of said crank-lever 58, whereby properly timed in and out swinging movements are imparted to said lever arms 54, and by the latter to said push-plates 41. Said crank-lever 58 is biased by suitable spring means to maintain operative engagement with the actuating cam 60 and at the same time to bias said push-plates 41 and their cooperating lever arms 54 to normal initial outswung positions. Such spring means may be applied to these parts in any suitable way; illustratively, as shown, said spring means may comprise suitably anchored pull-springs 61, which are respectively attached to the push-plates 41.

Means is provided for holding a carton body 10 within its containing conveyer pocket against both upward displacement and longitudinal shift while its ends are being closed by the manipulation of its end closure flaps 13 and their tuck-portions 14. This means is provided by an automatic clamp mechanism, and actuating means therefor adapted to properly time

the operation thereof, which, in the illustrative form thereof as shown, comprises a perpendicularly reciprocable slide-bar 62, slidably supported in a slideway block 63 which is affixed to 5 and which projects rearwardly from the underside of the bridge plate 50, so as to overhang the operative outgoing course of the carton conveyer means at a point where the carton end closure flaps 13 and their tuck-portions 14 are subject to manipulation by the previously described mechanism. Carried at the lower end of said slide-bar 62 is a cross-head 64 in which are affixed a pair of laterally spaced dependent clamp pins 65, preferably provided with sharp pointed free extremities. The means for actuating the slide-bar 62, to lower and raise its cross-head and the clamp pins 65 carried thereby, comprises an actuating lever 66 which is pivotally supported on a stationary fulcrum bracket 67. The free end portion of said actuating lever 66 is coupled to the upper end portion of said slide-bar 62 by a pin and slot connection 68. Said actuating lever extends from its pivotal point across the power transmission shaft 23, and is provided with a roller stud 69 adapted to operatively engage a clamp actuating cam 70 which is mounted on said power transmission shaft so as to be revolved thereby. Said cam 70 functions to effect properly timed application of the clamp pins 65 to a carton body 10 desired to be engaged thereby. Suitably arranged spring means 71 is provided for biasing said actuating lever 66 toward the cam 70 so as to maintain the roller stud 69 of the former in engagement with the latter.

Beyond the carton end closing mechanism are positioned suitably supported pressing rollers 72 between which the carton bodies 10 are successively carried by the advancing carton conveyer means. These pressing rollers 72 are adapted to press the closed and tucked end closure flaps 13 tightly home against the carton ends.

Beyond the pressing rollers 72, the upper outgoing course of the carton conveyer means passes downwardly around a supporting sprocket 73, from which the conveyer means extends rearwardly in its ingoing or return course. In passing around the sprocket 73, the pocket forming elements 16 of the conveyer means tend to separate or open out, so that the closed cartons may be discharged therefrom by gravity into an adjacent receiving chute 74, whereby to be discharged and removed from the machine.

In the operation of the carton closing mechanism, after an open carton body carried by the carton conveyer means is loaded with the blades B, or other product to be enclosed therein, the conveyer means advances the same through the carton closing mechanism. The carton conveyer means is intermittently actuated by suitable operating means (not shown), whereby each carton dwells momentarily at the goods filling station and at the station where the means for closing the end closure flaps 13 and tucking their tuck-portions 14 is located; the operation of said latter means and of the carton clamping or holding means being timed by their actuating cams to take place during a period of conveyer means dwell.

As filled cartons are carried along so as to enter between the folder bars 19, the nosings 22 at the rearward ends of the latter engage and fold inwardly the leading side tabs 11 to closed position, whereupon the kicker members 26 are

actuated to next close the trailing side tabs 12. As the cartons, with their side tabs closed, pass between the folder bars 19, the end closure flaps 13 will remain extended in the plane of the bottom wall of the carton body, so as to pass beneath folder bars 19 with their tuck-portions 14 extending therefrom in the plane thereof but freely beyond the outer faces of said folder bars. As the cartons are advanced by the progress of the conveyer means, and while the end closure flaps 13 are still engaged by the folder bars 19, the tuck-portions 14 are carried into engagement with the turn-over bars, so as to be first engaged by the upwardly and forwardly inclined portions 32 of the latter along which they are passed. These upwardly and forwardly inclined portions 32 of the turn-over bars cause said tuck-portions 14 to swing upward about a fold line intermediate the same and the end closure flaps 13, and while the latter are held down against up-swinging movement by the folder bars 19, until said tuck-portions 14 in turning stand perpendicular and contiguous to the inner faces of said turn-over bars (see Figs. 1, 2 and 3). As the thus up-swinged tuck-portions 14 continue to be advanced, the same traverse the heliciform surfaces 35 of the turn-over bars, by which they are gradually turned inward toward the open ends of the carton body 10. In the meantime, the end closure flaps 13 are carried beyond the forward ends of the folder bars 19, so as to be freed therefrom, and thereupon to be immediately engaged by the upwardly and forwardly inclined rearward end portions 38 of the tilters plates 37, thus initiating upswinging movements thereof (see Figs. 1 and 4). As the advancing movement of the carton is continued, the tuck-portions 14 continue to traverse the heliciform surfaces 35 of the turn-over bars, while the end closure flaps 13 continue to traverse the heliciform surfaces 40 of the tilters plates 37, until the initial up-swing of said closure flaps 13 is completed, and the tuck-portions 14, as angularly inturned relative to the closure flaps, are disposed with their free end edges opposed to the open ends of the carton body (see Fig. 5).

The end closure flaps and their tuck-portions are held in the described initially folded relation, while, by further advancing movement of the carton body 10, the same are entered and come to rest between the outswung folder plates 41 and beneath the guide fingers 44, and in so advancing escape from the ends of said turn-over bars and tilters plates (see Figs. 6 and 8). As will be observed more particularly by inspection of Fig. 8, the undersurfaces 46 of the guide fingers 44 lie in a plane slightly below the plane of the inside surface of the carton body 10, so that the free edges of the tuck-portions 14, when moved inward, will be guided to pass beneath the end edges of the carton top wall and into the interior of the carton body without risk of catching upon or being obstructed by said edges.

While the carton body 10 is held stationary by the dwell of the conveyer means, with the closure flaps and tuck-portions disposed as described, the actuating cam 70 of the carton clamping or holding means operates to first effect a down-swing of the lever 66 and accompanying downward movement of the clamp pins 65, whereby the latter respectively engage the carton body adjacent the respective ends thereof, thereby holding said carton body firmly against both up-

ward displacement and longitudinal shift, while the end closure flaps 13 are being closed and their tuck-portions 14 inserted into the carton body ends. The carton body being thus held, the actuating cam 60 functions to operate the folder plates 41, by imparting proper movement to the crank lever 58, and thus to the intergeared shafts 53, whereby to cause simultaneous in-swinging movements of the lever arms 54. Such movement of the lever arms 54 engages the roller studs 55 of the folder plates 41, so as to impart in-swinging movements to the latter. The inward movement of the folder plates 41 swings the closure flaps 13 across the open ends of the carton body to closed relation thereto, while at the same time thrusting into said open ends the tuck-portions 14 (see Figs. 7 and 9).

The end closure flaps of the carton body having been closed and tucked, the carton conveyer means advances the closed cartons so that, before discharge from the machine, they pass between the pressing rollers 72, whereby the closure flaps are pressed tightly home against the carton ends. This having been done, the conveyer means carries on the filled and closed cartons to the point of discharge, so that the same are released from the conveyer means and deposited in the take away chute, or other desired form of receiving means.

From the above description it will be understood that the instant invention provides a very simple, and yet highly efficient carton closing mechanism, and one which is especially well adapted for simultaneously operating upon both ends of a carton adapted to be closed by tuck type closure flaps.

It will be understood that various changes may be made in the disclosed constructions, and many apparently widely different embodiments of this invention could be made without departing from the scope thereof as defined by the following claims. It is therefore intended that all matter contained in the above description or shown in the accompanying drawings shall be interpreted as illustrative and not in a limiting sense.

I claim:

1. In carton closing mechanism having means for progressively advancing cartons through means to angularly bend carton end closure flaps and their tuck portions whereby to direct the latter toward open ends of the carton bodies, flap closing mechanism comprising normally outswung pivoted flap push-plate means, means to effect timed in and out swinging movements of said push-plate means, adjustably mounted stationary guide finger means directed toward the carton body ends with extremities thereof abutting end edges of carton body walls beneath which flap tuck portions are to be inserted and with their guide surfaces disposed in planes slightly below the planes of internal surfaces of said walls whereby to engage extremities of said flap tuck portions to guide movement thereof into the carton body ends, vertically reciprocable means to hold the carton bodies against displacement relative to said guide finger means while closure flaps and their tuck portions are being manipulated, and means to reciprocate said holding means to effect timed engagement and disengagement thereof with the carton bodies.

2. In carton closing mechanism having means for progressively advancing cartons through means to angularly bend carton end closure flaps and their tuck portions whereby to direct the latter toward open ends of the carton bodies, flap

closing mechanism comprising normally outswung pivoted flap push-plate means, means to effect timed in and out swinging movements of said push-plate means, adjustably mounted stationary guide finger means directed toward the carton body ends with extremities thereof abutting end edges of carton body walls beneath which flap tuck portions are to be inserted and with their guide surfaces disposed in planes slightly below the planes of internal surfaces of said walls whereby to engage extremities of said flap tuck portions to guide movement thereof into the carton body ends, vertically reciprocable means to hold the carton bodies against displacement relative to said guide finger means while closure flaps and their tuck portions are being manipulated, and means to reciprocate said holding means to effect timed engagement and disengagement thereof with the carton bodies, the carton body engaging elements of said holding means comprising sharp pointed clamp pins.

3. Carton end flap closing mechanism as defined in claim 1 including a pair of transversely opposed pressing rollers beyond said closing mechanism between which closed cartons are passed whereby to press the closed and tucked end closure flaps tightly home against the carton body ends.

4. In carton closing mechanism having means for progressively advancing cartons through means to angularly bend carton end closure flaps and their tuck portions whereby to direct the latter toward open ends of the carton bodies, flap closing mechanism comprising normally outswung pivoted flap push-plate means, means to effect in and out swinging movements of said push-plate means comprising oscillatable lever means, said push-plate means having laterally projecting stud means to receive actuating thrust of said lever means, and means to effect timed oscillation of said lever means to produce correspondingly timed in and out swinging movements of said push-plate means, adjustably mounted stationary guide finger means directed toward the carton body ends with extremities thereof abutting end edges of carton body walls beneath which flap tuck portions are to be inserted and with their guide surfaces disposed in planes slightly below the planes of internal surfaces of said walls whereby to engage extremities of said flap tuck portions to guide movement thereof into the carton body ends, vertically reciprocable means to hold the carton bodies against displacement relative to said guide finger means while closure flaps and their tuck portions are being manipulated, and means to reciprocate said holding means to effect timed engagement and disengagement thereof with the carton bodies.

5. In carton closing mechanism having means for progressively advancing cartons through means to angularly bend carton end closure flaps and their tuck portions whereby to direct the latter toward open ends of the carton bodies, flap closing mechanism comprising normally outswung pivoted flap push-plate means, means to effect in and out swinging movements of said push-plate means comprising oscillatable lever means, said push-plate means having laterally projecting stud means to receive actuating thrust of said lever means, and means to effect timed oscillation of said lever means to produce corre-

spondingly timed in and out swinging movements of said push-plate means, adjustably mounted stationary guide finger means directed toward the carton body ends with extremities thereof abutting end edges of carton body walls beneath which flap tuck portions are to be inserted and with their guide surfaces disposed in planes slightly below the planes of internal surfaces of said walls whereby to engage extremities of said flap tuck portions to guide movement thereof into the carton body ends, vertically reciprocable means to hold the carton bodies against displacement relative to said guide finger means while closure flaps and their tuck portions are being manipulated, and means to reciprocate said holding means to effect timed engagement and disengaging thereof with the carton bodies, the carton body engaging elements of said holding means comprising sharp pointed clamp pins.

20 6. Carton end flap closing mechanism as defined in claim 5 including a pair of transversely opposed pressing rollers beyond said closing mechanism between which closed cartons are passed whereby to press the closed and tucked end closure flaps tightly home against the carton body ends.

7. In carton closing mechanism having means for progressively advancing cartons through means to angularly bend carton end closure flaps and their tuck portions whereby to direct the latter toward open ends of the carton bodies, flap closing mechanism comprising normally outswung pivoted flap push-plates to oppose opposite ends of a carton body, means to simultaneously effect in and out swinging movements of said push-plates comprising a pair of intergeared rock shafts, lever arms respectively dependent from said rock-shafts for cooperation with the respective push-plates, each push-plate having adjacent to its free end portion a laterally projecting stud with which a corresponding lever arm cooperates, means to effect timed oscillation of said rock shafts, and their lever arms to produce correspondingly timed in and out swinging movement of said push-plates, adjustably mounted stationary guide fingers respectively directed toward opposite ends of a carton body with extremities thereof abutting end edges of the carton body walls beneath which flap tuck portions are to be inserted and with their guide surfaces disposed in planes slightly below the planes of internal surfaces of said walls whereby to engage extremities of said flap tuck portions to guide movements thereof into the carton body ends, vertically reciprocable means to hold the carton body against displacement relative to said guide fingers while closure flaps and their tuck portions are manipulated by said push-plates, means to reciprocate said holding means to effect timed engagement and disengagement thereof with the carton bodies, the carton body engaging elements of said holding means comprising sharp pointed clamp pins.

8. Carton end flap closing mechanism as defined in claim 7 including a pair of transversely opposed pressing rollers beyond said closing mechanism between which closed cartons are passed whereby to press the closed and tucked end closure flaps tightly home against the carton body ends.

GEORGE I. HOHL.
